UNITED STATES PATENT OFFICE.

WILLIAM SONNENBERG, OF WINONA, MINNESOTA.

MAGAZINE-FIREARM.

SPECIFICATION forming part of Letters Patent No. 787,800, dated April 18, 1905.

Application filed June 30, 1903. Serial No. 163,771.

To all whom it may concern:

Be it known that I, WILLIAM SONNENBERG, a citizen of the United States, residing at Winona, in the county of Winona and State 5 of Minnesota, have invented certain new and useful Improvements in Magazine-Firearms; and I do declare the following to be a full, clear, and exact description of the invention, such as will enable others skilled in the art to 10 which it appertains to make and use the same.

This invention relates to an improvement in magazine-firearms, the object of the invention being to construct a mechanism involving 15 a one-movement action and which will permit the loading and discharging of the gun without removal from the shoulder, as well as to provide a mechanism extremely rapid in its action to load and discharge the gun and 20 a mechanism compact within its casing.

With the above and other objects in view the invention resides in the novel construction, combination, and arrangement of parts, as will be hereinafter more specifically 25 described and then particularly pointed out in the claims, and in describing the invention in detail reference will be had to the accompanying drawings, forming a part of this specification, and wherein like numerals of reference 30 will indicate similar parts throughout the several views, in which—

Figure 1 is a longitudinal sectional view through the breech of the gun, showing the different parts involved in my invention assembled in position. Fig. 2 is a plan view of same, part of the casing being in section and the breech-block removed. Fig. 3 is a cross-section on line *a a*, Fig. 1. Figs. 4, 5, and 6 are detail views. Fig. 7 is a view of the trigger and carrier about to receive a cartridge from the magazine. Fig. 8 is a view of the trigger and carrier about to discharge a cartridge into the gun-barrel. Fig. 9 is a view of the trigger and carrier, the carrier being 45 in a non-loading position. Fig. 10 is a view of the breech-block and one of the operating-cams, the breech-block being in a firing position. Fig. 11 is a view of the trigger and hammer, the hammer about to strike the firing-pin. Fig. 12 is a view of the trigger and

hammer, the hammer being in a cocked position. Fig. 13 is a view of the trigger and part of the extracting mechanism. Fig. 14 is a longitudinal vertical section of the carrier. Fig. 15 is a bottom view of the breech-block. Fig. 16 is a longitudinal vertical section thereof. Fig. 17 is an end view of the breech-block within the casing, the casing being in section. Fig. 18 is a reverse view of the trigger and part of the carrier in dotted lines. Fig. 19 is a detail perspective view of the shell-extractor. Fig. 20 is a detail perspective view of the slide-bar.

Referring to the accompanying drawings, 1 indicates the lock case or receiver constructed to receive the mechanism and provided with a tang 2, adapted to be secured to the stock of the gun, this lock case or receiver being further provided with an oblong opening 3 in the top for the operation of the 65 breech-block and with a slot 4 to receive the hammer. The lock case or receiver is suitably secured to the rear end of the gun-barrel 5 preferably by forming an interior bushing in the forward end of the lock case or receiver and threading the barrel into said bushing. This bushing is also provided with an opening to receive the inner end of the magazine-tube 6, located, preferably, underneath 70 the barrel, as in the usual practice, and in 75 which the cartridges are carried and fed by means of a spring-pressed plunger 7, as in the usual manner.

The breech-block 8 is pivotally hung in the lock case or receiver on a pin 9 and normally—85 that is, when the gun is not in action—closes the opening 3, the said breech-block having an oscillatory movement in the lock case or receiver.

Referring to Fig. 16, it will be seen that the 90 breech-block is bored throughout its length adjacent to the upper face to receive the firing-pin 10, the bore and pin being of correspondingly different diameters and the pin being held normally in the retracted position 95 by means of a spring 11, arranged on the pin between an annular shoulder thereon and an annular shoulder in the bore of the block. This pin is grooved on its lower face, as at 12, to receive a set-screw 14 to prevent the with- 100

drawal of the firing-pin and to limit its movement.

The breech-block has a lower hinged web 15, normally held depressed by means of a spring 16 and provided with a curved flange or rib 17, (see Figs. 15 and 16,) so that when an empty shell is ejected from the barrel it will strike against the curved flange or rib, and be thus guided to and ejected through the opening 18 provided therefor in one side of the lock casing or receiver. (See Fig. 17.) The lower face of the breech-block is provided with a groove conforming to the shape of the flange or rib and receiving the latter as the breech-block is elevated and the web closes on the breech-block.

The lock casing or receiver is in two parts-- the upper part, as heretofore described, and the lower part 19, constructed with a tang 20 for attachment to the stock of the gun. At its forward end this lower part of the lock-case is secured by a screw 21 to the forward end of the upper part. In the forward end of the lower portion of the lock-case is hinged 25 by means of a pin 22 the shell-extractor 23, the particular shape of which is best seen in Fig. 19 of the drawings, being cut away in one side edge to receive the end of the magazine-tube and at its upper end having a semi-circular recess registering with the bore of the barrel. A spring-pressed bolt 24 is mounted in one wall of the lower part of the lock-case and serves as a cushion for the sudden impact of the shell-extractor as the latter is ejecting 30 a shell and forces the extractor back into position when the ejecting power is released.

The cartridge-carrier 25 has two rearwardly-extending straps 26, provided near their rear ends with openings to receive the pivot-pin 40 27, which also serves for the hammer 28. The cartridge-carrier is bored longitudinally to receive the cartridge and a slide-bar 29, which latter has a loop 30 on its rear end to receive the upper end of the trigger, whereby the 45 slide-bar is actuated by and simultaneously with the trigger.

The slide-bar 29 near its forward end is provided with a slot 31, through which is passed a pin, which is also passed through the rear end 50 of a spring loading-plunger 32, to eject the cartridge from the carrier into the barrel, the spring allowing the full stroke of the sliding bar 29 and pressing the cartridge into position. Further backward movement of the 55 plunger is prevented by the pin 31^a. The lower edges of the rearwardly-extending straps or sides of the cartridge-carrier are formed with a series of cams, as and for the purposes hereinafter set forth.

60 The trigger 32^a has an upwardly-extending portion or end 33, that protrudes into the loop 30 of the slide-bar and carries a roller 34 in its upper end. The said trigger carries pins 35, which engage in slots 36 in tumblers 37, 65 one at each side of the trigger, and which re-

volve under the haunches 37^a of the breech-block and serve to operate and hold the latter in place. The trigger carries a pin 38, which when the trigger is operated rearwardly engages the rear end of a locking-pin 39, that 70 is mounted in the wall of the lower part of the lock-case and forces said pin forwardly against the spring-plunger 39^a for the shell-extractor, forcing the said plunger back and permitting the ejector to assume the position 75 for the insertion of a cartridge into the barrel. A pin 40, mounted in the lower part of the lock-case, is engaged by the trigger when the latter is forced forwardly, and this pin operates the sear 40^a, releasing the locking-pin 39 and allowing the spring-plunger 39^a to force the shell-extractor rearwardly to eject the shell. A spring-operated dog 41 is carried by the trigger, which operates upon the cam-surface on the under side of one side 85 of the carrier and is guided in its position by a pin 42. (Shown plainly in Fig. 18.)

A pin 43 extends from one side of the trigger, which engages the cam-surface on the opposite side of the carrier. The trigger 90 also has spurs 44 and 45 and is pivoted by a pin 46, passing through it and extending into the casing at each side. At 46^a is pivoted a short arm 47, engaged by a spring 48, secured to the lower part of the casing.

The sear 40^a is pivoted at 49 and at its front end is provided with a tooth 50, which engages a notch 51, Fig. 13, in the under side of the locking-bar 39. The locking-bar is provided at its forward end with a right-angled projection 52, which engages the spring-plunger 39^a. 95

The hammer 28 is provided at its top with a thumb-catch 53, on its forward edge with a spring-lip 54, at its lower extremity with a 105 notched portion 55, and on its rear edge a cut-out portion 56. It is pivoted on the pin 27 and is spring-held by the springs 57 and 58, which are secured to the lower tang.

The front end of the sear 40^a is pressed upward by a spring 59, seated in a recess in the lower casing. The tumblers 37 are pivoted on short screw-pivots 60, inserted from the outside through the lower casing and into the tumblers.

115 The spring-plunger 39^a is provided with a side extension or lug 63, that engages the extractor 23.

The operation of the mechanism is as follows: Commencing with the position of the several parts when the trigger is in its extreme position forward, as shown in Fig. 1, the pin 40 of the sear 40^a is flush with the outer surface of the lower casing. In that position dog 41, Fig. 18, rests in a depression 61 of the shell-carrier. A cartridge is shown in the carrier and the barrel-chamber is empty. The first movement backward of the trigger causes dog 41 to raise or lift the shell-carrier on its pivot 27, further movement of the trig- 120 125 130

ger continuing lifting carrier until dog 41 reaches the point 62 of the carrier. When the dog reaches this point, the carrier has reached its highest point of lifting with the 5 cartridge opposite the barrel-chamber ready to be inserted therein. (See Fig. 8.) The trigger has then moved about one-quarter way back. Continuing the backward movement of the trigger, the spur 45 on the trigger 10 engages the spring-lip 54 on the hammer, Fig. 11, moves the hammer backward, the process of cocking begins immediately, and continues throughout the backward movement of the trigger and until the tripping of the hammer 15 takes place. Still continuing the movement backward of the trigger, the pin or projection 38 on the trigger, Fig. 13, pushes against the bolt 39, the rear end of which bears against said pin or projection, while the forward end 20 of the bolt rests against the spring bolt or plunger 39^a, while the projection 63 of the plunger rests against the shell-extractor 23, so that the first movement of the trigger pushes bolt 39 forward, and thereby pushes 25 plunger 39^a also forward, at the same time compressing the plunger-spring. Pushing the plunger forward relieves its pressure from the shell-extractor 23 and permits the latter to swing on its hinge or pivot forward. When 30 the pressure of the plunger is withdrawn from the extractor, the spring bolt or pin 24, Fig. 2, forces the extractor into its recess and out of the path of the carrier. The forward movement of the bolt continues as long as the 35 trigger moves backwardly, moving the plunger 39^a forward, so that when the trigger is entirely back and ready to trip the hammer the end of the plunger is some distance ahead of the extractor. After bolt 39 has pushed 40 plunger 39^a its full distance the projection or tooth 50 of the sear 40^a is forced by the spring 59 into the notch 51, and thereby locks it in place, preventing the plunger 39^a from moving either the bolt or the extractor if the 45 hold on the trigger is released. Still continuing the backward movement of the trigger, the pins 35 on each side of the trigger press against the upper sides of the slots 36 in the tumblers 37, turning said tumblers upon their 50 pivots 60, thereby swinging the upper portions backward. The upper portions move in the circular depressions in the haunches of the breech-block. When the trigger is forward, the tumblers rest as shown in Fig. 55 1, holding the upper part of the breech-block carrying the firing-pin in place. When the tumblers move toward the rear, as the trigger moves back, the curve in the haunches is so formed as to impart no movement to the 60 upper part of the breech-block. In fact, the tumblers only touch for a short space at the extremity of the curve during their travel from one end to the other. The tumblers reach the rear of the curve when the trigger 65 is almost back and then tip the forward end of the breech-block down and in line with the barrel-chamber. (Shown in Fig. 10.) These four movements begin at the same time with the beginning of the backward movement of the trigger. When the trigger has moved 70 back about one-quarter distance, the shell-carrier is opposite the barrel-chamber. With a further movement backward of the finger-hold of the trigger the upper part moves the loading-plunger 32 forward and pushes the 75 cartridge into the barrel-chamber. When this movement takes place, the roller 34 in the upper end of the trigger engages the inclined front wall 64 of the loop 30, the purpose of the roller being to cause as little friction as possible and to prevent binding. While loading takes place the hinged part 17 of the breech-block rests against the under side of the upper part, the forward end fitting back of the lip 65, Fig. 10, out of the way of the carrier, 80 with the top of the carrier resting against the under side thereof. At this point the breech-block is in its highest position. As soon as the loading-plunger has traveled its full length and has deposited the cartridge into the barrel-chamber the tumblers 37 have reached near to the end of the curve of the breech-block, depressing the front end thereof, and the front end presses the carrier down. At 85 this point of the operation the dog 41 has reached and rests at a point 66 of the carrier, Fig. 18, the angle being such as to compress the spring 67. The loading rod or plunger being formed in two parts and being spring-connected permits the end to slide down without binding during the downward travel of the carrier. As the trigger continues to move back the front end of the breech-block falls, its movement at this time being quite rapid, until opposite the barrel-chamber. When 90 this position is reached, the carrier is a little above its lowest position, opposite the magazine, and supported thereby by pin 43 a trifle too high to permit a cartridge to leave the magazine, Fig. 9. The trigger has now reached 95 its extreme backward movement and hinge-lip 54 trips out of engagement with the spur 45 and the hammer is forced forward by the spring 57. The front or head of the hammer strikes the rear end of the firing-pin. The pin 100 strikes the rim of the cartridge and explodes it. The spring 58 then rebounds the hammer sufficient to relieve the pressure from the firing-pin, permitting the pin to be withdrawn from contact with the shell by the spring 105 11. This completes the entire operation by the backward movement of the lower part of the trigger. The forward movement of the trigger is assisted by the spring 48, or, if desired, the spring can be strong enough to 110 bring the trigger back automatically. The movement of the trigger forward causes the tumblers 37 to raise the top of the breech-block, leaving the hinged web down, and the spring 16 assists in holding it down. At this 115 120

time the upper end of the trigger moves the loading rod or plunger backward, preparing the carrier to receive another cartridge from the magazine. No other movement takes place until the trigger strikes the pinion 40 under the sear 40^a. The top part of the breech-block is now at its extreme height, with the hinged portion below the barrel-chamber. When the trigger forces the pin 40 upward, it causes the sear to rock and disengage the tooth thereof from the sliding bolt 39, relieving the spring-plunger 39^a. The force of the spring drives the bolt back against the pin or projection on the trigger, and the side projection 63 of the plunger strikes the extractor, forcing it from the barrel-chamber, carrying the empty shell with it, and throws the shell with considerable force against the curved portion of a hinged portion of the breech-block and out of the gun through the opening 18 in the side of the casing. At the same time the pin 43 has changed its position on the bottom of the carrier sufficient to permit the carrier to drop opposite the magazine. To bring the carrier down positively, the spur 44 on the trigger engages the hook 68 on the carrier and pulls the carrier down until the opening in the end of the carrier permits the cartridge to slip into place by force of the magazine-spring. During this time the spur 45 has moved over the spring-lip 54 until the spring snaps it into place. This completes the entire operation.

The cartridges in the magazine are held in place by the front face of the carrier, which never moves beyond the opening of the magazine and has a downwardly-extending lip for that purpose.

The hammer can be cocked by hand and held in a cocked position until released by a pressure upon the trigger. When it is cocked by hand, the notch 55 on the hammer engages the spur 45 on the trigger, all other movements being the same whether cocked by hand or trigger.

Having thus fully described my invention, what I claim, and desire to secure by Letters Patent, is—

1. A magazine-firearm comprising a cartridge-carrier for conveying the cartridge to the barrel, a plunger carried by said carrier for delivering the cartridge from said carrier, a shell-extractor, and a trigger, the movement of the latter controlling the operation of all the first-named elements.

2. A magazine-firearm comprising a pivoted cartridge-carrier, a pivoted trigger having an extended upper portion, a spring-operated dog arranged on one side of said extended portion, a pin secured to the opposite side of said extended portion, said pin and dog engaging said carrier, and a plunger for delivering the cartridge from said carrier.

3. A magazine-firearm comprising a pivoted cartridge-carrier having a series of cam-surfaces on its lower face, a pivoted trigger hav-

ing an extended upper portion carrying a spring-dog and a pin adapted to engage said cam-surfaces, and a plunger carried by said carrier for ejecting the cartridges therefrom.

4. A magazine-firearm comprising a pivoted cartridge-carrier having a series of cam-surfaces on its lower face, a plunger for ejecting the cartridges from said carrier, and a pivoted trigger having an extended portion carrying a spring-operated dog at one side and a pin at the other side for engaging said cam-surfaces, whereby the movement of the trigger operates the carrier and the plunger.

5. A magazine-firearm comprising a pivoted cartridge-carrier having a series of cam-surfaces on its lower face, a plunger for ejecting the cartridges from said carrier, a pivoted trigger, a spring-operated dog carried by said trigger, a pin secured to said trigger, and a friction-roller carried by said trigger for operating said plunger.

6. A magazine-firearm comprising a pivoted cartridge-carrier, a cartridge-ejecting device carried by said carrier and consisting of a slide-bar and a plunger loosely connected together with a spring arranged between them; and a pivoted trigger engaging said slide-bar and carrier to operate the same.

7. A magazine-firearm comprising a cartridge-carrier having a cartridge-ejecting device consisting of a slide-bar and a plunger slidably secured together, a pivoted trigger having an extended upper portion, a friction-roller carried by said trigger and adapted to engage and operate said slide-bar, a spring-dog carried by said trigger, and a laterally-projecting pin carried by said trigger, the dog and pin being adapted to engage and operate said carrier when the trigger is pulled backward.

8. A magazine-firearm comprising a pivoted trigger having an extended upper portion carrying a laterally-projecting pin, a sliding bolt operated by said pin, a spring-plunger operated by said bolt, and a shell-extractor operated by said plunger upon the release of said bolt.

9. A magazine-firearm comprising a pivoted trigger having an extended upper portion carrying a laterally-projecting pin, a sliding bolt operated by said pin, a spring-plunger operated by said bolt, a shell-extractor operated by said plunger upon the release of said bolt, and a spring-bolt to return said extractor into place.

10. A magazine-firearm comprising a pivoted trigger having an extended upper portion carrying a laterally-projecting pin, a sliding bolt notched on its lower side and operated by said pin, a spring-held pivoted sear to engage said notch, a spring-plunger, a shell-extractor operated by said plunger when the sear releases the bolt, and a spring-bolt to return said extractor into place.

11. In a magazine-firearm, a pivoted trig-

ger having an extended upper portion carrying a laterally-projecting pin, a notched sliding bolt operated by said pin, a spring-held pivoted sear for engaging said sliding bolt, a 5 pin engaging said sear, a spring-plunger, a shell-extractor operated by said plunger when the sear releases said bolt, and a spring-operated bolt for returning said extractor into place.

10 12. A magazine-firearm comprising a pivoted trigger having an extended upper portion carrying laterally-projecting pins, tumblers pivoted to the side casing and operated by said pins, and a pivoted breech-block carrying a firing-pin, said tumblers acting on said breech-block to tilt it into line with the barrel-chamber.

15 13. A magazine-firearm comprising a pivoted trigger having an extended upper portion carrying laterally-projecting pins, tumblers pivoted to the side casing and operated by said pins, and a pivoted breech-block having curved haunches and carrying a firing-pin

operated by said tumblers to tilt it into line with the barrel-chamber.

25

14. A magazine-firearm comprising a pivoted trigger having an extended upper portion carrying laterally-projecting pins, tumblers pivoted to the side casing and operated by said pins, a pivoted breech-block having 30 curved haunches and carrying a firing-pin, said breech-block being tilted by said tumblers into line with the barrel-chamber, and a hammer to operate said firing-pin.

15. A magazine-firearm comprising a trigger, a shell-ejector and means for operating the same, and a breech-block having a pivoted spring-held web curved rearward and outward to deflect the ejected shell.

35 In testimony whereof I affix my signature in presence of two witnesses.

WILLIAM SONNENBERG.
